PRODUCING ARTIFICIAL SILK

Theodor Grauer, Horn, Thurgau, Switzerland

Application November 3, 1934, Serial No. 751,401
In Germany November 13, 1933

9 Claims. (Cl. 18—8)

This invention relates to an improved process of treating artificial silk and like material subsequent to spinning, and to an appliance for carrying this process into effect.

According to the invention I employ so-called spinning rims. The rims are conveyed from the spinning machine into the troughs, wherein the material is to be treated subsequently, not in an ungoverned manner, but in an exactly prescribed manner, wherein care is taken that the rims remain in the previous mutual position. The distance existing between the rims on the spinning machine is maintained during their conveyance and the rims are conveyed to the troughs by gravity and roll on their own circular edges, the rims of one machine being rolled into the trough in unison as a whole. Each one machine has allotted to it one trough the length of which corresponds to that of the machine. The rims arrive in the respective trough by gravity and with the same mutual distance as they are disposed in the spinning machine. In the trough are provided suspended or bottom-mounted elastic packing rings between the rims which rings are laterally shiftable and interconnected by distance chains. After the rims have rolled into the trough they are pressed against one of the end walls thereof by means of an end plate likewise provided in the trough, whereby they are packed against one another and against the trough. The subsequent treatment of the filament may then take place under pressure or in vacuo. The washing treatment under pressure is of particular advantage.

The present process and appliance further afford the notable advantage that no fixing members are required for the rims as is the case in similar arrangements, although they rest in the trough with their cylindrical surface extending horizontally. On the contrary, the rims may rest on the bottom of the trough by means of projecting flanges which protect the filament from damage. On that end against which the rims are pressed the trough is provided with a pipe connection through which, in the case of the above-mentioned treatment under pressure, the treating liquids are supplied. The liquids penetrate through the filament coils and are drained either through an overflow arranged on the upper portion of the trough or through a bottom valve.

After the treatment of the rims in the trough, the end plate is withdrawn whereupon the rims may be grasped mechanically or by hand on their upper edges and lifted from the trough.

When the end plate is retired, the intermediate packing rings are spread out from one another by means of a distance chain which can be expanded only to such an extent that the plates exactly come into the prescribed position. 5

In some cases it will be of advantage not to press the rims against the one end wall of the trough, but to press them together from both sides toward the center of the trough by means of two end plates. In this case the liquid has to 10 be fed through one of the end plates.

In order that the invention may be clearly understood and readily carried into effect, an embodiment of the appliance adapted for the performance of the process is illustrated diagrammatically by way of example in the accompanying drawing in which

Figure 1 is a section on line I—I of Figure 2 and shows a trough for the treatment of the filament with fully reeled rims therein, 20

Figure 2 is a cross section on line II—II of Figure 1,

Figures 3 and 4 are sections of modified troughs on reduced scale,

Figures 5, 6 and 7 show details of the construction of the trough on various scales, 25

Figures 8 and 9 show the suspended packing rings and their mutual distances.

I denotes a trough which is of about the same length as the respective spinning machine and 30 is situated in such a manner relatively to the latter, that the rims can be rolled directly thereto. The trough may be mounted stationarily on the ground or for rotation about a longitudinal axle 3, as illustrated in Figure 3. 35

In the trough I is arranged an end plate or cover 4, Figures 1 and 6, which by two arms 5 and 6 projects beyond the upper edge of the trough and can be shifted in longitudinal direction by means of rollers 7, 8 that run on U-rails 9 provided on both outer sides of the trough I. 40

The cover 4 can be pressed against the rims 15 placed in the trough by means of a mechanism, Figures 1—4, which comprises a hand lever 11 mounted on a fixed transverse shaft 12, situated 45 about at the level of the central axis of, and outside the trough (in Figure 6 this shaft for sake of clearness is shown as situated below the trough) and two cam slot segments 13 and 14 rigid with shaft 12, Figures 6 and 7, which are engaged by 50 the rollers 7 and 8. The cover 4 is fitted on its inner side with a packing ring 16 of rubber or the like. The same is the case with the intermediate rings 17. Cover 4 and rings 17 press the rims against one another and thus pack them. 55

It is of importance that the rims 15 are constructed so as to withstand the packing pressure without being deformed. To this end the rims are strengthened on their base by annular ribs 5 27 projecting laterally on both sides. The intermediate rings 17 therefore by their rubber packings press against these annular ribs 27 and not against the walls proper of the rims.

The intermediate rings 17 are suspended in the 10 trough 1 by means of lateral arms 19, 20 which rest on the upper edge of the trough. The arms 19, 20 are further connected with one another and with the cover 4 and the trough by chain-like links 21, 22, Figures 2 and 5, so that the distance existing between each two rings 17 and the trough wall and cover 4 is exactly limited in outward but not in inward direction by the length of the links 21, 22.

When the cover 4 is retired, the intermediate 20 rings 17 are drawn from one another to such an extent as admitted by the links 21, 22. They have then the pitch *b* marked in Figure 8. This pitch corresponds to the pitch or position of the rims on the spinning machine, that is, to the 25 mutual spacing in which the rims are reeled in the machine.

All rims 15 are rolled in unison from the spinning machine into the trough by means of suitable conveying means which are not represented 30 for sake of clearness. Each rim drops into the space existing between the respective packing rings 17 onto longitudinal ribs 23, 24, Figures 2 and 6, made from rubber or the like and mounted on the bottom of the trough 1. These ribs have 35 perforations 28, Figure 1, to allow draining of the liquid from the trough.

After all rims have entered the trough, the cover 4 is pressed against them by means of the mechanism 11—14, that is, by depression of the hand lever 11 all rims at once are packed. They have then the pitch marked by *a*, Figures 1 and 9.

The liquid intended for the treatment of the filament is supplied for example through a pipe 25, Figure 1, so as to arrive in the inner space of the rims, and penetrates through small holes provided in the bottom of the rims and through the spires of the filament. The liquid collects on the bottom of the trough and is drained through an overflow 29 or bottom valve 26, Figure 1.

It is further possible to dry the filament after the washing treatment by means of hot dry air which is forced through the apparatus.

The rims are withdrawn in the same simple manner as they are inserted. To this end the cover 4 is retired by means of the mechanism 55 11—14, whereby the mutual distance between the rings 17 is enlarged by the links 21, 22, so that the rims can be easily removed by hand or by a suitable lifting device. Or the trough is tilted about 60 its longitudinal axle 3, Figure 3, so that all rims together drop onto a belt conveyor or the like (not shown).

Instead of one cover 4, two covers may be provided which are shiftable toward one another and press the rims 15 and rings 17 together. In this case one of these covers has mounted on it the pipe connection for the liquid and the drying air.

What I claim and desire to secure by Letters 70 Patent is:—

1. Process of handling artificial filaments after spinning, which comprises winding the filaments within the peripheral grooves of a plurality of separate coaxially and closely arranged felly-shaped rims of considerably greater diameter

than width, continuing the winding to a depth which leaves the outer surface of each package within the outer circumference of its rim, and then rolling the rims simultaneously in substantially their same relative positions into a treating 5 tank.

2. Process of handling artificial filaments after spinning, which comprises winding the filaments within the peripheral grooves of a plurality of separate coaxially and closely arranged felly-shaped rims of considerably greater diameter than width, continuing the winding to a depth which leaves the outer surface of each package within the outer circumference of its rim, then rolling the rims simultaneously in substantially 15 their same relative positions into a treating tank, and then squeezing the group of rims axially to form a tight unit.

3. Apparatus for handling artificial filaments after spinning, comprising a tank, a group of 20 separate felly-shaped perforated rims of considerably greater diameter than width resting on their peripheries in said tank in horizontal axial alinement, the filaments being wound within the outwardly opening peripheral grooves of said rims 25 without projecting beyond the edges of said grooves, means mounted on said tank for squeezing said group of rims axially to form a tight unit, and means for introducing a fluid into the hollow space within said unit. 30

4. Apparatus for handling artificial filaments after spinning, comprising a tank, a group of 35 separate felly-shaped perforated rims of considerably greater diameter than width resting on their peripheries in said tank in horizontal axial alinement, the filaments being wound within the outwardly opening peripheral grooves of said rims without projecting beyond the edges of said 40 grooves, a set of packing rings adapted to be inserted between the said rims, means mounted on said tank for squeezing said group of rims axially to form a tight unit, and means for introducing a fluid into the hollow space within said unit.

5. Apparatus for handling artificial filaments after spinning, comprising a tank, a group of 45 separate felly-shaped perforated rims of considerably greater diameter than width resting on their peripheries in said tank in horizontal axial alinement, the filaments being wound within the outwardly opening peripheral grooves of said rims without projecting beyond the edges of said 50 grooves, an end plate adapted to close the opening of one outermost rim of said group, means on said tank for moving said end plate to squeeze said group of rims against a cross wall of said tank to 55 form a tight unit thereof, and means to introduce a fluid through said cross wall into the space within said unit.

6. Apparatus as described in claim 5, wherein 60 said end plate is provided with arms extending over the side walls of the tank and downward, guide means being provided for the ends of said arms, said means for moving said end plate being connected to said arms. 65

7. Apparatus for handling artificial filaments after spinning, a comprising a tank; a set of packing rings; an end plate; means whereby said packing rings and end plate are mounted upon said tank so as to stand upright in parallel relation and so as to be movable axially; means interconnecting said end plate and said cross wall to permit a limited relative movement thereof, means on said packing rings engaged by said interconnecting means so that each packing ring 70 75

is pulled apart from its neighbor as said end plate is moved outward from said cross wall; a set of felly-shaped rims adapted to fit into the spaces between said packing rings, between said end plate and the adjacent ring, and between said cross wall and the adjacent ring, the filaments being wound within the outwardly opening peripheral grooves of said rims; and means to draw said end plate toward said cross wall to squeeze all said elements into a tight hollow unit.

8. Apparatus as described in claim 3, wherein said tank is tilttable.

9. Apparatus for handling artificial filaments subsequent to spinning, comprising a set of felly-shaped perforated rims each adapted to have a filament wound into its outwardly facing peripheral groove, said rims having axially projecting flanges serving as packing and stiffening flanges, said rims being adapted to be squeezed together axially to form a tight hollow unit.
